US0D1076885S

(12) **United States Design Patent** (10) **Patent No.:** **US D1,076,885 S**
(45) **Date of Patent:** **** May 27, 2025**

(54) **WALL MOUNT FOR AN AUDIO DEVICE**

(71) Applicant: **Sonos, Inc.**, Santa Barbara, CA (US)

(72) Inventors: **Vincent Wang**, East Palo Alto, CA (US); **Edward Mitchell**, Thousand Oaks, CA (US); **Eduardo Salazar**, Reseda, CA (US); **Rasmus Breitholtz**, Malmö (SE)

(73) Assignee: **SONOS, INC.**, Goleta, CA (US)

(**) Term: **15 Years**

(21) Appl. No.: **29/912,404**

(22) Filed: **Sep. 18, 2023**

Related U.S. Application Data

(63) Continuation-in-part of application No. 29/868,435, filed on Dec. 2, 2022, now Pat. No. Des. 1,073,651.

(57) **CLAIM**

The ornamental design for a wall mount for an audio device as shown and described.

DESCRIPTION

FIG. 1 is a front elevational view of a wall mount for an audio device showing the new design;

FIG. 2 is rear elevation view thereof.

FIG. 3 is a top plan view thereof.

FIG. 4 is a bottom plan view thereof.

FIG. 5 is a right side view thereof.

FIG. 6 is a left side view thereof.

FIG. 7 is a first perspective view thereof; and,

FIG. 8 is a second perspective view thereof.

The features shown in broken lines form no part of the claimed design.

1 Claim, 8 Drawing Sheets
